UNITED STATES PATENT OFFICE.

BYRON JACKSON, OF SAN FRANCISCO, CALIFORNIA.

SERIES HIGH-PRESSURE CENTRIFUGAL PUMP FOR HIGH HEADS.

SPECIFICATION forming part of Letters Patent No. 729,870, dated June 2, 1903.

Application filed March 4, 1903. Serial No. 146,063. (No model.)

To all whom it may concern:

Be it known that I, BYRON JACKSON, a citizen of the United States, residing in the city and county of San Francisco, State of California, have invented certain new and useful Improvements in Series High-Pressure Centrifugal Pumps for High Heads; and I hereby declare the following to be a full, clear, and exact description of the same.

10 My invention relates to improvements in series pressure centrifugal pumps for raising and forcing water by increasing pressure in successive steps, using the centrifugal impactive and cumulative forces set up by two or more rotating runners mounted upon the same shaft; and it consists of an improved adjustable automatic balance for end thrust on shafting and of casing-sections inclosing suitably-curved waterways between the discharge of one runner and the entrance of the next in the series, also the parts and the combination of parts hereinafter described and claimed.

The object of my invention is to provide a 25 specific pump construction that is simple, compact, efficient, practical, and operative, and to utilize to the greatest extent possible the combination of centrifugal and impact forces and the energy due to the whirling velocity and momentum of the water as it passes from one runner to the other and to obviate the losses of power that are incident to pumps of this class as far as possible by change of the course and velocity of water, also to provide in combination therewith an automatic hydraulic end-thrust counterbalance means in the nature of an adjustable valve or plug in line with the pump-shaft, whereby the pressure exerted in a counterbalance-chamber 30 may be controlled. The present invention in this latter respect is an improvement on the balancing device as specified and illustrated in a patent issued to me entitled "Centrifugal pump" and dated November 11, 1890, No. 440,252, also one other patent issued to F. H. Jackson and assigned to me, entitled "End-thrust counterbalance for centrifugal pumps and shafting," and issued January 29, 1901, No. 666,869, to which reference is made 45 for further specifications than contained in this application. To achieve these objects, I

construct a series high-pressure pump substantially as follows and as shown in the drawings, in which—

Figure 1 is a longitudinal section through 55 a series vertical pump having impelling-runners revolving in a horizontal plane shown in section. Fig. 2 is the same as Fig. 1, except the shaft is horizontal and the runners revolve in vertical plane. Fig. 3 is a vertical transverse section on line $x-x$ in Figs. 1 and 2. Fig. 4 is a section through $y-y$ in Figs. 1 and 2.

A represents a circular case-section forming the first step or unit in series and inclosing a large annular chamber concentric with the driving-shaft 4, in which chamber revolves one of the runners 3.

A' is a second circular case-section forming the second step or unit in the series and is a 70 duplicate of A.

B is the involute case-section and the third and final step in the series and has a tangential discharge, as usual in single-step pumps.

3 represents the runners of the inclosed 75 type keyed to the revolvable shaft 4.

5 is the suction T or L; 5', the discharge-nozzle; 6, adjustable plug-balancing valve, to be described later; 7 and 7', cap-screws to adjust balancing-plug; 8, pressure-counterbalance chamber between last runner of series and casing; 8', pressure counterbalance-chamber for intermediate runners; 9, shaft end bearing; 9', shaft-bearings within the casing; 10, curved waterways cored in 80 the casing, guiding water from one runner to the other; 11, Fig. 3, impelling-runner vanes; 12, annular flange cast on runner, forming a wall of pressure-chamber 8; 13, annular flange cast on pump-cover, forming sliding 85 joint with annular flange 12. These rings have a sliding fit to allow discharge pressure-water to percolate into chamber 8; 14, suction inlet-joint of a runner; 15, corresponding sliding joint on pump-case; 16, 90 cover to pump-case section A; 17, annular flange cast on back of runner, opposite suction-inlet horizontal-type pump; 18, annular flange cast on the inside of case horizontal pump, said flanges forming a running and 95 sliding joint between the discharge-pressure and the inlet-pressure; 19, port through hub

of last runner in series communicating with chamber 8; 19', similar ports in hubs of the other runners.

The drawings here show both horizontal and vertical shaft three-step series high-lift pumps suitable for four-hundred-foot head. The pump-cases A and A' are duplicate and may be repeated to any desired number. The case 2 is involute, and final discharge, 5 takes place therefrom at a tangent, as is usual with single-step pumps. The first case-section in the series forms the cover for the one following it, and the two are held together by means of studs in one side of the case and a projecting flange on the opposite side, as shown in Figs. 1 and 2, and all the discharge from the periphery of the preceding runner is conveyed through curved waterways 10 to the center of the next runner in the series. These curved waterways 10 are made in one side of the interior of the pump-case. They are preferably cored in the casting, as shown in the drawings, and their surfaces may be finished smooth to improve the efficiency in high-duty pumps. The shapes and direction of these curved waterways are geometrical on lines corresponding to the waterways through the impelling-runner, the object being to maintain uniform sectional area and long radius curves, thus avoiding any sudden change of direction of the water flow and utilizing the momentum and energy due to the whirling velocity and impact of the water discharged 35 from periphery of one runner to the center of the next in series.

The runners 3 (shown in section) are of the inclosed type provided with suction or inlet openings, all facing in the same direction and with radial and backwardly-curved vanes 11 on geometrical lines, as shown in Fig. 3.

The waterways 10, Fig. 4, are laid out on the traveling lines of the discharging water 45 from the runner, which vary with the velocity of the runner and the quantity of water discharged, and the observance of a due relationship between the curve and pitch of these waterways and the velocity and quantity of water is of the utmost importance.

It will be noted that the runner-vanes 11 are curved backward from center to periphery in relation to the direction of rotation of the runner and to the line of water discharge, 55 while the water-passages 10 will curve forwardly in a line of water discharge, conveying the water to the center of the next runner. By so doing the kinetic forces set up in the water by the whirling velocities are not lost, but are passed on to the next runner in the series.

By widely separating the runner-chambers, inclining the planes of the passage-ways 10 relative to the axis of the runners, and utilizing long radius curves where changes of direction are necessary and having the walls 10^a, Fig. 4, separating the passage-ways con-

tinuous and curving the runner-vanes backwardly I provide for a natural progression from one runner to another and always continue the water in the same direction. Consequently there is a greater cumulated force at discharge than where the passage-ways from one runner to another describe a loop or where they lie in a plane substantially at right angles to the runner-shaft and where the runner-vanes curve forwardly in the direction of rotation of the runners, as in certain types of centrifugal pumps.

A supplemental counterbalance for each intermediate runner is formed in the chamber inclosed by the annular flange 17 opposite the inlet and flange 18 on the casing, each of said chambers connecting through the hub by the ports 19', said flanges forming a running and sliding joint between the discharge and inlet pressure.

Power from any suitable source is applied to drive shaft 4.

The operation of the pump is as follows: 90 The pump being filled with water, the impelling-runners are driven at a suitable speed or number of revolutions per minute to discharge water at the desired head when water is drawn in at the suction 7 or 1.5 and is forced through the forwardly-curved waterways 10 of the pump, as indicated by the arrows, and is delivered at the discharge-nozzle 5' at a pressure equal to the sum of all the series of pressures. It is known that the suction and discharge pressure in a centrifugal pump is unbalanced on the two sides of the inclosed type of impellers and that this inequality of pressure amounts approximately to the number of inches of area of the suction-inlet multiplied by the pounds pressure of the total head pumped against. This pressure, however, is never equal to the discharge-pressure, which is always varying, depending on the head, and may be more on one side of the runner, depending on the central position of runner, the pressure per inch being greatest on the side having the greatest clearance between runner and pump-case, because of skin friction on the side of runner producing a pumping effect.

To compensate for this varying pressure, caused by the end travel of the pump-shaft changing the clearance-space between the sides of the pump-case and the runner, I have provided the plug-valve 6, 110 which is movable in the pump-casing in line with shaft 4 and port 19. This plug (and by "plug" is meant its equivalent, the sleeve 6 of Fig. 2) has a sliding fit with the walls of the latter and is adapted to be advanced or retracted 115 to enter port 19 or be withdrawn therefrom, according as it is desired to allow more or less back-pressure water in chamber 8 to enter the runner again for the purpose of restoring or maintaining equilibrium. In operation the 120 back pressure due to pump discharge will seek relief between flanges 12 13 and produce a pressure in chamber 8 to counterbalance the thrust exerted from the suction end of the

runner again for the purpose of restoring or maintaining equilibrium. In operation the 130 back pressure due to pump discharge will seek relief between flanges 12 13 and produce a pressure in chamber 8 to counterbalance the thrust exerted from the suction end of the

shaft. Whenever the pressure in chamber 8 exceeds the pressure on the opposite side of the runner, the latter will move with the shaft a short distance longitudinally until an outlet from this chamber is afforded through port 19 and around the plug into the runner again, (at a point of greatly-reduced pressure.) When the pressure exerted from the suction end is greater than from the discharge end, the runner and shaft will move toward the plug, closing the opening between the hub and plug, when the pressure from the discharge entering chamber 8 will again resist further travel in that direction. In this manner the differential of pressure upon one side or the other acts constantly under ordinary conditions to balance the runner and retain it in its proper central position within the casing. Under some circumstances, however, of variation in hydraulic pressure and of the driving force, as in the multiple or series form of pump, it has been found desirable to change the point of equilibrium of the runners relative to the casing. The plug 6 and its adjusting-screws afford a simple and perfect means for controlling this movement. Thus if it is desired to shift the point of equilibrium farther toward the suction end of the pump in order, say, to accommodate a particular motor it is only necessary to slack up screws 7 and by means of screws 7' move the end of the plug in the required distance, whereupon the runners must move correspondingly before the excess pressure in chamber 8 can escape into port 19. To shift the point of equilibrium in the other direction, the plug is moved in that direction accordingly.

In constructing the vertical pump, Fig. 1, the inlets of all runners 3 are faced upward and are made of sufficient area that when pumping against the proposed head the pressure in pounds times the area will equal the total pressure or more of the shaft and revolving parts. The area of balancing-chamber 8 should be sufficient that when this chamber is connected through the port 19 in the hub of runner with the lower pressure at the entrance or interior of runner the upward thrust will be reduced to exactly the weight of shaft and revolving parts, thus making an exact equilibrium between weight of shaft and water-pressure pumped against.

In constructing a horizontal pump, Fig. 2, a balance-chamber on the opposite side of the runner of the same area of the suction-inlet is made of the two balance-rings 17 and 18 on the runner and the casing, respectively, and connected through ports 19' to the suction pressure at the inlet to runner, thus equalizing the pressure at inlet.

To balance the unequal pressure on the two sides of the runner, caused by skin friction and greater clearance on one side than the other, I construct the balance-chamber 8 and plug 6 the same as described on the vertical pump.

Having thus described my invention, what I claim, and desire to secure by Letters Patent, is—

1. In a high-pressure centrifugal pump, the combination of an incased revoluble shaft, a runner upon said shaft, an annular space between the runner and the end of the casing adjacent to the discharge-passage, the latter and said chamber being in constant communication, a passage connecting said chamber and the interior space of the runner, and a plug movable in relation to the end of the runner by which said passage may be controlled whereby the point of equilibrium of the runner may be varied arbitrarily. 70

2. The combination in a high-pressure centrifugal pump, an incased revoluble shaft, a runner on said shaft, a flange on the side of the runner opposite to the inlet-passage, a fixed flange on the casing corresponding to said flange, and forming therewith a joint through which pressure-water may percolate into the annular inclosed space between the casing and runner, a port communicating with said space and the interior of the runner, and a movable plug in line with said shaft and adapted to fit within said port for the purpose described. 80

3. The combination in a centrifugal pump, of a casing with inlet and discharge openings, a shaft revoluble within the casing and having a limited longitudinal movement, a runner upon said shaft, a movable sleeve in which the inner end of the shaft is journaled, annular passages between the end of the casing and the runner and in the runner-hub, connecting the discharge-opening of the casing and the interior of the runner, and means by which said sleeve may be shifted to arbitrarily regulate said passages. 95

4. The combination in a centrifugal pump, of an incased revoluble shaft, one or more runners carried thereon, a non-rotatable sleeve in which the discharge end of the shaft is rotatable, an annular chamber between the casing and the side of the runner adjacent to the sleeve, said chamber having communication with the discharge of the runner, and also with the interior of the runner, and means by which said sleeve may be shifted in the line of the shaft to regulate said communication between said chamber and the interior of the runner. 100

5. The combination in a series high-pressure centrifugal pump, of an incased revoluble shaft having a limited reciprocating movement, a plurality of runners on said shaft having each a central receiving-opening and a peripheral discharge-outlet, curved passageways between said runners through which the water passes successively from one runner to the other, each of said runners having a flange, a corresponding flange on the casing forming a running joint with the first-named flange, annular counterbalance-chambers inclosed by said flanges, and ports in the hubs of the runners opposite the receiving-open- 110 115 120 125 130

ing communicating with said last-named chambers.

6. In a series high-pressure centrifugal pump, the combination of a revoluble shaft, a plurality of impelling-runners of the inclosed type, rigid thereon, and turnable therewith, said runners having flanges on their sides opposite the inlet, corresponding flanges on the pump-case, the two flanges forming a running and sliding joint between the discharge-pressure and the inlet-pressure, ports connecting the chambers so inclosed by said flanges with the passage-way of the runners, said runner passage-ways curved backwardly on geometrical lines and correspondingly curved waterways in the pump-casing through which the water discharged from one runner is delivered to a succeeding runner through a central inlet on the side adjacent to the discharging-runner.

7. In a series high-pressure centrifugal pump, the combination of two or more impelling-runners of the inclosed type, a shaft to which said runners are made fast, conjoined case sections or units in which said runners are operable, said runners having annular flanges on the back opposite the inlet, a corresponding flange on the pump-case sections, the two flanges forming a running

and sliding joint between the discharge and inlet pressure and connected with the passage-way in the runner by a port through the hub of the runner, said runners having waterways curved backwardly on geometrical lines, and said case-sections, except the last, having corresponding waterways curved forward guiding and conveying the water from one pump-case section to the other.

8. In a series high-pressure centrifugal pump, the combination of an incased revoluble shaft, carrying a plurality of runners of the inclosed type, said runners having backwardly-curved vanes, passage-ways cored in the casing and curved on geometrical lines relative to said runner-vanes, counterbalance-chambers between each runner and the casing, and an adjustable plug-valve in line with the shaft and operable in relation to the counterbalance-chamber last in series for the purpose of balancing the hydraulic thrust with the end thrust of the driving-shaft and limiting the end play within working limits.

In witness whereof I have hereunto set my hand.

BYRON JACKSON.
